UNITED STATES PATENT OFFICE.

GEORGE M. GRAHAM, OF CHICAGO, ILLINOIS, ASSIGNOR TO G. A. EDWARD KOHLER, OF CHICAGO, ILLINOIS.

FITTING FOR REINFORCED CONCRETE STRUCTURES.

No. 879,163.

Specification of Letters Patent.

Patented Feb. 18, 1908.

Application filed October 17, 1907. Serial No. 397,848.

To all whom it may concern:

Be it known that I, GEORGE M. GRAHAM, a citizen of the United States of America, and a resident of Chicago, in the county of Cook 5 and State of Illinois, have invented certain new and useful Improvements in Fittings for Reinforced Concrete Structures, of which the following is a specification.

This invention relates to fittings or couplings for reinforced concrete constructions, and more especially to the type of such fittings forming the subject matter of my prior Letters Patent No. 865,489 of Sept. 10, 1907. And the present improvement has for its object to provide a simple and efficient structural formation and combination of parts whereby an easy assemblage of the skeleton reinforcing frame and the fittings is attained, and with which a very rigid and substantial 20 connection of the parts is provided, all as will hereinafter more fully appear.

In the accompanying drawings: Figure 1, is a top view of the fitting in place upon the tubular reinforcing frame of a concrete structure, with one of the vertical columns of said frame in section. Fig. 2, is a similar view with the upper section of the fitting removed and with the vertical attaching bolts in section. Fig. 3, is a side elevation showing the fitting in place. Fig. 4, is a vertical section on line $x-x$ Fig. 3. Fig. 5, is a perspective view of the upper member of the fitting. Fig. 6 is a perspective view of the lower member of the fitting. Fig. 7, is a side elevation 35 of a modified form of the fitting. Fig. 8, is a vertical section on line $x'-x'$ Fig. 7.

Similar numerals of reference indicate like parts in the several views.

Referring to the drawings, 1 and 2 represent the respective upper and lower sections 40 of the fitting, the meeting surfaces of which are horizontal and formed by annular horizontal webs or flanges 3 and 4, which in turn are provided with a series of elongated orifices for the passage of the bolts 5 by which the sections are secured together.

6 and 7 are secondary annular horizontal webs or flanges having a spaced relation to the aforesaid webs or flanges 3 and 4, and integrally connected thereto, as hereinafter described.

8 and 9 are annular necks formed on the webs or flanges 6 and 7, and having a smaller diameter than such flanges in order to pro-

vide supporting abutments or rims 10 and 11 55 at the points where such necks join such flanges. Said necks are adapted to fit within the bore of the tubular columns 12 and 13, and to be capable of limited expansion therein, and to such end the respective upper and 60 lower sections 1 and 2 are formed with radial slits 14 and 15, to permit of expansion after the parts are assembled; such expansion may be effected by tapering keys driven into said slits, or by means of the radial bolts 16 65 and 17 by which the ends of the aforesaid columns 12 and 13 are secured to the annular necks 8 and 9. The elongated form of the orifices for the attaching bolts 5 heretofore referred to, is to avoid interference on the 70 part of said bolts with the above described expansion of the fitting sections.

18 are bolts passing through flanges 19 at the margins of the slits 14 and 15, and adapted to impart initial contraction to the fitting 75 sections so that they may be readily introduced into place.

20 and 21 are pluralities of radially arranged semi-circular webs which form the connection between the above described 80 flanges of the respective fitting sections and to such end are integrally formed with said flanges as shown. Such webs provide semi-circular recesses or cavities in the opposed surfaces of the flanges 3 and 4, and so that 85 each opposed pair of such semi-circular cavities will constitute a single cylindrical cavity for the reception of the end of a tubular girder 22 of the skeleton reinforcing structure as shown. In an ordinary form of the present fitting four of such semi-circular cavities will be formed in a fitting section, and in right-angle relation, as shown in the drawings, and as so constructed the fitting is adapted to be placed upon any part of the 95 exterior of a tubular frame girder 22, and adapted longitudinally thereon to the proper position to receive the ends of companion girder 22. Any other usual arrangement of 100 said cavities may be made to meet the varied requirements of the art, and without departing from the scope of this part of the present invention.

A material part of the present construction consists in the arrangement of each 105 semi-circular web 20, 21, midway of the walls of the annular necks 8 and 9 and so that portions of said webs 20 and 21 will ex-

- tend into the open central portion of the fitting sections. Such construction provides a very compact and substantial support or connection for the tubular frame members, and is adapted to withstand in an effective manner the usual lateral strains imposed in the assemblage of the parts of a skeleton structure.
- 23 are open top recesses formed in the top surface of the flange 4 of the lower fitting section in right angle relation to the semi-circular cavities thereof and opening into said cavities as shown. Such recesses are formed wholly in said lower fitting section and to such end the upper surface of such section will be positioned a sufficient distance above the center upon which the circular outline of the semi-circular cavities are generated, and for the purpose hereinafter set forth.
- 24 are holding pins extending transversely through the ends of the tubular girders 22 aforesaid, and intersecting the longitudinal axis thereof. The ends of such pins project at the sides of the girders and are adapted to rest in the open top recesses 23 aforesaid to positively hold the tubular girder members against independent longitudinal movement in the fittings.
- 25 Where two girders 22 of a skeleton reinforcing structure are placed in adjacent relation to constitute a duplex girder as fully set forth in my former patents Nos. 865,489 and 865,490 of Sept. 10, 1907, two of the present fittings will be placed in corresponding relation and held separate by a section of tubing of the required length and diameter; it is preferable, for a number of uses, however to connect the lower section of the upper fitting with the upper section of the lower fitting by an integrally formed tubular member 25, as illustrated in Figs. 7 and 8.
- Having thus fully described my said invention what I claim as new and desire to secure by Letters Patent is:
1. A fitting for reinforced concrete structures, comprising in combination, upper and lower sections provided with necks adapted to fit the interior of tubular frame members and formed with radial slits, and means for effecting an expansion of said sections.
  2. A fitting for reinforced concrete structures, comprising in combination, upper and lower sections, each consisting of a pair of horizontal flanges a series of semi-circular webs connecting said flanges together and annular necks projecting from one flange of each section, and means for securing said sections together.
  3. A fitting for reinforced concrete structures, comprising in combination, upper and lower sections, each consisting of a pair of horizontal flanges a series of semi-circular webs connecting said flanges together and annular necks projecting from one flange of each section, and bolts passing through adjacent flanges of the sections to secure the same together.
  4. A fitting for reinforced concrete structures, comprising in combination, upper and lower sections, each consisting of a pair of horizontal flanges a series of semi-circular webs connecting said flanges together and annular necks projecting from one flange of each section, said sections being formed with radial slits, means for effecting an expansion of said sections, and means for securing the sections together.
  5. A fitting for reinforced concrete structures, comprising in combination, upper and lower sections, each consisting of a pair of horizontal flanges a series of semi-circular webs connecting said flanges together and annular necks projecting from one flange of each section, said sections being formed with radial slits, means for effecting an initial contraction of the sections, and means for securing the sections together.
  6. A fitting for reinforced concrete structures, comprising in combination, upper and lower sections, each consisting of a pair of horizontal flanges a series of semi-circular webs connecting said flanges together and annular necks projecting from one flange of each section, said sections being formed with radial slits, means for effecting an initial contraction of the sections, the same comprising flanges at the margins of the slits and bolts passing through said flanges, and means for securing the sections together.
  7. A fitting for reinforced concrete structures, comprising in combination, upper and lower sections, each consisting of a pair of horizontal flanges a series of semi-circular webs connecting said flanges together and annular necks projecting from one flange of each section, and means for securing said sections together, one of said sections having transverse recesses in its meeting face adapted to receive the ends of a holding pin carried by a tubular girder or the like.
  8. A fitting for reinforced concrete structures, comprising in combination, upper and lower sections, each consisting of a pair of horizontal flanges a series of semi-circular webs connecting said flanges together and annular necks projecting from one flange of each section, said sections being formed with radial slits, means for effecting an expansion of said sections, and means for securing the sections together, one of said sections having transverse recesses in its meeting face adapted to receive the ends of a holding pin carried by a tubular girder or the like.
  9. A fitting for reinforced concrete structures, comprising in combination, upper and lower sections, each consisting of a pair of horizontal flanges a series of semi-circular webs connecting said flanges together and annular necks projecting from one flange of each section, and means for securing the sections together.

each section, said sections being formed with radial slits, means for effecting a contraction of said sections, and means for securing said sections together, one of said sections having 5 transverse recesses at its meeting face adapted to receive the ends of a holding pin carried by a tubular girder or the like.

10. A fitting for reinforced concrete structures, comprising in combination, upper and lower sections, each consisting of a pair of horizontal flanges a series of semi-circular webs connecting said flanges together and annular necks projecting from one flange of each section, said sections being formed with 15 radial slits, means for effecting an initial contraction of said sections, the same comprising flanges at the margins of the slits and bolts passing through said flanges, and means for securing the sections together, one of said 20 sections having transverse recesses in its meeting face adapted to receive the ends of a holding pin carried by a tubular girder or the like.

11. A fitting for reinforced concrete structures, comprising in combination, upper and 25 lower sections, each consisting of a pair of

horizontal flanges a series of semi-circular webs connecting said flanges together and annular necks projecting from one flange of each section, said sections being formed with 30 radial slits passing through one of the semi-circular webs aforesaid, means for effecting an expansion of said sections, and means for securing the sections together.

12. A fitting for reinforced concrete structures, comprising in combination, upper and lower sections, each consisting of a pair of horizontal flanges a series of semi-circular webs connecting said flanges together and annular necks projecting from one flange of 40 each section, said sections being formed with radial slits passing through one of the semi-circular webs aforesaid, means for effecting an initial contraction of the sections, and means for securing the sections together. 45

Signed at Chicago, Illinois this 2nd day of October 1907.

GEORGE M. GRAHAM.
